UNITED STATES PATENT OFFICE.

CLAIR L. FARRAND, OF FOREST HILLS, NEW YORK; ERNEST ROSS, OF EAST ORANGE, NEW JERSEY; AND ALBERT D. SILVA, OF FOREST HILLS, NEW YORK; SAID ROSS AND SAID SILVA ASSIGNEES TO FARRAND MFG. CO. INC., OF LONG ISLAND CITY, NEW YORK, A CORPORATION OF NEW JERSEY.

ACTUATING DEVICE FOR LOUD SPEAKERS.

Application filed June 23, 1927. Serial No. 200,814.

This invention relates to electromagnetic actuating devices for radio loud speakers and the like.

One object of the invention is to provide an improved armature assembly for electromagnetic actuating devices and an improved electromagnetic actuating device embodying that assembly.

Another object of the invention is to provide an improved electromagnetic actuating device which is compact and inexpensive to manufacture.

A further object is to provide an electromagnetic actuating device having improved means for holding the pole pieces in fixed relation with respect to each other.

The improved armature assembly and a complete electromagnetic actuating device embodying the armature assembly are illustrated in the accompanying drawings in which:

Fig. 1 is a perspective view of the parts of the armature assembly before they are assembled;

Fig. 2 is a perspective view of the completed armature assembly;

Fig. 3 is a longitudinal section through the armature assembly taken on the line 3-3 of Fig. 2. In this figure, however, a speech coil has been added which is not shown in Fig. 2;

Fig. 4 is a perspective view showing all of the parts of the actuating device, except the permanent magnet, the parts being shown in proper relative positions but slightly separated to show how they fit together;

Fig. 5 shows the parts illustrated in Fig. 4 clamped together into a complete unit;

Fig. 6 is a transverse section through the assembled unit shown in Fig. 5, the section being taken on the line 6-6 of Fig. 5;

Fig. 7 is a front elevation of a complete actuating device showing how the unit of Fig. 5 may be applied to the permanent magnet;

Fig. 8 is a top plan view of the actuating device shown in Fig. 7; and

Fig. 9 is a horizontal section taken on the line 9-9 of Fig. 7.

As shown in Fig. 1 the parts of the armature assembly include two sheet metal channel shaped members 1 and 2 each of which

has a bottom wall 3 and side flanges 4. The bottom wall 3 of each channel shaped member has integral end portions 5 which extend longitudinally beyond the flanges 4 for the purpose hereinafter described.

The parts of the armature assembly also include sheet metal flanges 6 and 7 having central rectangular openings 8. The armature is shown at 9. It has soldered to it a rod 10 which constitutes part of the connections to the diaphragm.

The bottom wall 3 of each channel shaped member has an indentation 11 which forms an inwardly extending projection 12. Each side wall of the armature 9 is provided with an indentation 13.

When the parts shown in Fig. 1 are assembled the channel shaped members 1 and 2 are positioned against the armature so that the projections 12 on the channel shaped members engage in the indentations on the armature. The flanges 6 and 7 are then slipped over the ends of the channel shaped members in such a way that the end portions 5 extend beyond the flange members. The parts are held in this position and soldered together to form the complete unit shown in Fig. 2. From this figure it will be seen that the flange members 6 and 7 together with the channel shaped members 1 and 2 form a spool or bobbin for the speech coil. The channel shaped members 1 and 2 in conjunction form a hollow core for the bobbin and the armature 9 extends through the hollow core, the indentations 13 on the armature and the projections 12 on the channel members serving as a pivotal support for the armature as shown in Fig. 3.

The extensions 5, measured in the direction of vibration of the armature, are wider than the ends of the armature so that they act as spacing means for the pole pieces when the armature assembly is combined with the other parts of the device.

The spool or bobbin shown in Fig. 2 is wound with a coil of wire represented at 100 in Fig. 3.

Fig. 4 shows the manner in which the armature assembly and the speech coil are combined with all of the other parts of the actuating device except the magnet. These parts include two pole pieces 15 and 16.

Each pole piece may be a flat strip of metal having at its end a U-shaped opening 17 which forms on each pole piece two poles 18 and 19. The pole pieces may, if desired, be one strip of metal, but in the present instance they are composite, each pole piece comprising two juxtaposed strips of metal similarly formed. The parts shown in Fig. 4 include two sheet metal channel shaped members 20 and 21 which act as clamps to hold the pole pieces rigidly in position when the parts are assembled. There is also shown in Fig. 4 a terminal board 22 made of insulating material having a pair of terminals 23 secured to it to which the leads from the radio set may be connected. These terminals are connected with clips 23' to which the ends of the speech coil may be soldered. A spring member 24 to which 20 is soldered a rod 25 completes the parts shown in Fig. 4.

When the parts shown in Fig. 4 are assembled and clamped together they form the unit shown in Fig. 5. All of the parts shown in Fig. 4 are provided with openings which are adapted to register when the parts are assembled so that bolts 26 and 27 may be passed through them to clamp the parts together. When so clamped together the two poles on one pole piece overlap with respect to the corresponding poles on the other pole piece to form two air gaps in which the ends of the armature are located. The extensions 5 on the channel shaped members 1 and 2 are clamped between the pole pieces and act as definite spacing means for the poles so that the size of the air gaps is predetermined. It is only necessary to clamp the pole pieces against the extensions 5 without the necessity of careful adjustment or regulation of the air gaps because the size of the air gaps is definitely fixed by the spacers 5.

The side flanges of the clamping member 20 are relatively deep at one end as shown at 26 so that they extend to the pole piece 16 and are relatively shallow at the other end as shown at 27 so that they project over and extend to the pole piece 15. Likewise, the side flanges of the clamping member 21 are relatively deep at 28 so as to extend to the pole piece 15 and are relatively shallow at 29 to project over and extend to the pole piece 16. The outer member at one side of the unit shown in Fig. 5 is the terminal board 22, and the outer member at the other side of the unit is the spring 24. The spring 24 is adapted to be connected with the rod 10 on the armature 9, but the connection is not made until after all of the parts are clamped together. After the parts are clamped together the armature is held in its central position, as by inserting a thin strip of metal in the gap at each side of the armature, and then the rod 10 is soldered to the

spring 24. When the strips of metal are removed the armature will remain in its central position. The projections 12 on the channel shaped members 1 and 2 and the indentations 18 in the armature are so located 70 that the armature will be centrally pivoted in the channel shaped members. Therefore, the sizes of all the gaps between the ends of the armature and the poles will be the same.

The outer ends of the pole pieces 15 and 75 16 are provided with openings 30 and 31 so that the projecting ends of the pole pieces may be bolted directly to the extremities of a U-shaped magnet 32 as shown at 33 and 34 in Fig. 7. As the outer ends of the pole 80 pieces do not lie in the same plane it is necessary to insert between one pole piece and the corresponding leg of the magnet one or more metallic washers shown at 35 in Figs. 8 and 9.

The armature is preferably made of 40% nickel steel and the pole pieces are preferably made of 4% silicon steel. The channel shaped members 1 and 2, and flange members 6 and 7 of the spool or bobbin may be 90 made of brass and the clamping members 20 and 21 may also be made of brass.

The actuating device was especially designed for use in radio loud speakers of the cone type, but it may be used for actuating any kind of a diaphragm or as an actuating device in general. When used as an actuating device for a radio loud speaker it may be mounted in any suitable way with respect to the diaphragm. The rod 25 is 100 connected with the diaphragm. In the case of a cone type speaker it is connected with the apex of the cone. The vibrations of the armature 9 are transmitted by the rod 10 to the spring 24. The rod 25 transmits the vibrations from the spring 24 to the diaphragm.

The actuating device herein disclosed is inexpensive to manufacture as nearly all of its parts may be made of stamped metal. 110 Only a few parts are required and the construction is extremely compact as will be apparent, especially from Fig. 5.

Inasmuch as the armature is centrally mounted with respect to the channel shaped members 1 and 2, and inasmuch as the extensions 5 on the channel shaped members, measured in the direction of vibration of the armature, are wider than the ends of the armature the pole pieces may be quickly 115 clamped in place without giving any thought to the size of the air gap because the extensions 5 act as definite spacing means for the poles, and when one end of the armature is held in its central position before 120 the rod 10 is soldered to the spring 24 it thereafter remains in its central position with all gaps between the armature and the poles of the same size. The clamping members 20 and 21 constitute simple, but effec- 125 130

tive means for holding the pole pieces rigidly in position.

We claim:

1. An armature assembly for electromagnetic actuating devices comprising an armature, and at least one sheet metal member to which the armature is pivoted, an integral portion of said sheet metal member being arranged laterally beside an end portion of the armature and being of greater width measured in the direction of vibration of the armature than the end of the armature whereby said integral portion of the member may serve as spacing means for pole pieces.

2. An armature assembly for electromagnetic actuating devices comprising an armature, and at least one sheet metal side member arranged laterally of the armature and to which it is pivoted, said side member having integral end portions arranged laterally of the ends of the armature and of greater width measured in the direction of vibration of the armature than the ends of the armature whereby they may act as spacing means for pole pieces.

3. An armature assembly for electromagnetic actuating devices comprising an armature, a sheet metal side member located at each side of the armature, means for holding said side members in fixed position with respect to each other, a pivotal connection between the side members and the armature, said side members having integral end portions arranged laterally of the ends of the armature, the end portions of said side members measured in the direction of vibration of the armature being of greater width than the end portions of the armature for the purpose described.

4. An armature assembly for electromagnetic actuating devices comprising an armature, a sheet metal hollow core in which the armature is pivoted, and flange members to which the hollow core is secured and forming with the core a bobbin for a coil of wire, said core having integral end portions projecting beyond the side flanges and arranged laterally of the ends of the armature, said end portions of the core measured in the direction of vibration of the armature being wider than the ends of the armature whereby said end portions of the core may serve as spacing means for pole pieces.

5. An armature assembly for electromagnetic actuating devices comprising an armature, a sheet metal channel shaped member located at each side of the armature and forming in conjunction a hollow bobbin core, means for pivotally supporting the armature in said core, and flange members to which the channel members are secured and forming with said core a bobbin for a coil of wire, said channel members having end portions projecting beyond said flanges

and arranged laterally of the ends of the armature, said end portions of the channel members measured in the direction of vibration of the armature being wider than the ends of the armature whereby said end portions of the channel members may serve as spacing means for pole pieces.

6. An armature assembly for electromagnetic actuating devices comprising an armature, a sheet metal channel shaped member located at each side of the armature and forming in conjunction a hollow bobbin core, each channel shaped member having an indentation forming an inwardly extending projection, and the armature having indentations to receive said projections whereby the armature is pivoted to vibrate between the channel members, and flange members to which the channel members are secured and forming with said core a bobbin for a coil of wire, said channel members having end portions projecting beyond said flanges and arranged laterally of the ends of the armature, said end portions of the channel members measured in the direction of vibration of the armature being wider than the ends of the armature whereby said end portions of the channel members may serve as spacing means for pole pieces.

7. An armature assembly for electromagnetic actuating devices comprising a bobbin having a sheet metal hollow core and end flanges, and an armature positioned within said core, said core having indentations forming inwardly extending projections and said armature having indentations to receive said projections whereby the armature is pivotally mounted within the core.

8. An armature assembly for electromagnetic actuating devices comprising an armature support formed of sheet metal, and an armature associated with said support, the sheet metal support having indentations forming inwardly extending projections and the armature having indentations to receive said projections whereby the armature is pivotally mounted on the support.

9. An armature assembly for an electromagnetic actuating device comprising an armature support and an armature associated with said support, said support having inwardly extending projections and the armature having recesses to receive said projections whereby the armature is pivotally mounted on said support.

10. An actuating device for loud speakers comprising a magnetic field structure having a pair of poles, an armature an end of which is located between said poles, at least one sheet metal member to which the armature is pivoted, an integral portion of said sheet metal member extending between the poles, and means for clamping said integral end of said member between the poles, said integral end of said member measured in the

direction of vibration of the armature being wider than the end of the armature whereby the end portion of said member serves as spacing means for said poles.

11. An actuating device for loud speakers comprising a magnetic field structure having two pairs of poles, an armature each end of which is located between the two poles of one pair, a hollow sheet metal core structure 10 in which the armature is pivoted intermediate its ends, said sheet metal core structure having end portions each of which extends between the two poles of one pair, and means for clamping said portions between the poles, said end portions of the core structure measured in the direction of vibration of the armature being wider than the end portions of the armature whereby said end portions of the core structure serve 20 as spacing means for the poles.

12. An actuating device for loud speakers comprising a magnetic field structure having two pairs of poles, an armature each end of which is located between the two poles of 25 one pair, a channel shaped member located at each side of the armature, end flanges to which said channel shaped members are secured thereby forming a bobbin with a hollow core in which the armature is located, 30 a speech coil on said bobbin, said channel shaped members having integral extensions positioned between the poles, means for pivotally mounting the armature on said channel shaped side members so that it is capable 35 of vibrating in said core, and means for clamping the integral extensions of said channel shaped members between the poles,

said integral extensions of said channel shaped members measured in the direction of vibration of the armature being wider than the end portions of the armature whereby they serve as spacing means for the poles. 40

13. An electromagnetic actuating device for loud speakers and the like comprising a magnet, substantially flat pole pieces secured thereto the ends of which are in overlapping relation, means for holding the pole pieces in fixed position said means comprising a pair of members each of which has a relatively deep portion extending to one pole 50 piece and a relatively shallow portion projecting over and extending to the other pole piece and means for clamping said members together with the pole pieces between them. 55

14. An electromagnetic actuating device for loud speakers and the like comprising a magnet, substantially flat pole pieces secured thereto the ends of which are in overlapping relation, means for holding the pole pieces in fixed position said means comprising a pair of channel-shaped members having cut out portions in their side walls so that each member has relatively deep flanges at one end extending to one pole piece and relatively shallow flanges at the other end 65 projecting over and extending to the other pole piece, and means for clamping said members together with the pole pieces between them. 60

In testimony whereof we affix our signatures. 70
